UNITED STATES PATENT OFFICE

2,473,754

AMPLIFIER CIRCUITS WITH DOUBLE CONTROL

Johan Lodewijk Hendrik Jonker and Petrus Hubertus Johannes Agnes Kleynen, Eindhoven, Netherlands, assignors, by mesne assignments, to Hartford National Bank and Trust Company, Hartford, Conn., as trustee

Application May 9, 1946, Serial No. 668,550
In the Netherlands July 19, 1941

Section 1, Public Law 690, August 8, 1946
Patent expires July 19, 1961

5 Claims. (Cl. 179—171)

1

The invention relates to amplifiers circuits comprising an electric discharge tube with double control, one of the controls being effected with the aid of deflection members. The term "control" is to be understood to mean not only the normal control by an incoming signal but also the application of a variable biasing potential for volume control and the like.

Amplifier circuits in which two control voltages act upon two control grids of a discharge tube are known. A known example of such a tube is the so-called control hexode. These tubes entail the drawback that an important reaction of the second control space on the first takes place and through this reaction the proper operation of the tube is affected. If one of the control grids is replaced by a deflection control system, other difficulties occur since deflection control in itself is highly insensitive. In fact, if use is made of deflection plates which are maintained at a negative potential, a very high space charge occurs. The presence of the space charge results in unsharp beams occurring, while in some cases also a reaction may take place. If the deflection plates are made positive, the beams are sharper, it is true, but the sensitivity is lower due to greater electron speed.

Applicant has found that these drawbacks may be obviated with the aid of a circuit and a tube according to the present invention. This circuit comprises a discharge tube with double control systems in which one of the control systems, preferably the second, is a deflection system and at least one of the deflection plates has supplied to it a control voltage obtained by amplification of a voltage supplied to the grid of the tube.

When using this circuit it is possible to obviate on the one hand the difficulties which occur by the return of electrons to the first control space, whereas on the other hand the sensitivity considerably increases and one of the deflection elements may be connected without objection to a point of positive voltage.

The amplified control voltage to be supplied to the deflection means may be derived from an impedance included in the anode circuit or in the screen-grid circuit of another amplifying tube contained in the apparatus.

According to one particular embodiment of the present invention, however, this control voltage is taken from the screen grid of the tube in which the two controls take place and in which the screen-grid conductor includes an impedance across which the amplified control voltage occurs. This impedance may be constituted by a

2

resistance which is by-passed for the signal frequency so that the deflection means have solely supplied to them a variable direct voltage for volume control or the like.

According to another embodiment, one of the deflection members is connected in the above-described manner to the screen grid of the tube and the other member to the control grid. The latter deflection member may, however, also be connected to a point of fixed positive or negative potential.

The invention will be explained more fully by reference to the accompanying drawing showing, by way of example, a circuit and a tube according to the invention.

In the figure, 1 indicates an electric discharge tube containing a cathode 2, a control grid 3, a screen grid 4, an anode 5 and two deflection plates 6 and 7. The tube contains in addition a plate 8, which is preferably connected to the anode and serves for an advantageous electron distribution in accordance with the anode potential, and a body 9, preferably in the form of a rod, which is at low potential and prevents troublesome secondary emission phenomena between the anode and the positive deflection plate. As can be seen from the drawing, a control voltage for volume control, together with the incoming signal, is impressed on the control grid 3 via the circuit 10. The screen grid is connected to the deflection plate 7 via the conductor 11 and the screen-grid conductor includes a resistance 12 between the screen grid and the source of supply 13, which resistance is by-passed for the signal frequency by a condenser. The deflection plate 6 is also connected to the control grid via the circuit 10. The anode lead includes in addition the output circuit 14 and the cathode lead includes the parallel connection 15 of a resistance and a condenser which serves to generate the desired fixed grid biasing potential.

We claim:

1. An amplifier circuit arrangement, comprising an electron discharge tube having an electron-emitting cathode, a control grid, a screen grid, an electron beam deflection system comprising a first deflection electrode, a second deflection electrode arranged in cooperative association with said first deflection electrode and an anode, means to couple said first deflection electrode to the grid of said tube, means to connect said second deflection electrode to said screen grid, means to apply operating potentials to said tube, means to apply a signal voltage to the control grid of said tube,

and an output load impedance means connected to said anode.

2. An amplifier circuit arrangement, comprising an electron discharge tube having an electron-emitting cathode, a control grid, a screen grid, an electron beam deflection system comprising a first deflection electrode, a second deflection electrode arranged in cooperative association with said first deflection electrode and an anode, means to couple said first deflection electrode to the grid of said tube, means to connect said second deflection electrode to said screen grid, a resistor connected to said screen grid, means to short circuit said resistor for currents of frequency of said signal voltage, means to apply operating potentials to said tube, means to apply a signal voltage to the control grid of said tube, and an output load impedance means connected to said anode.

3. An amplifier circuit arrangement, comprising an electron discharge tube having an electron-emitting cathode, a control grid, a screen grid, an electron beam deflection system comprising a first deflection electrode, second and third deflection electrodes arranged in cooperative association with said first deflection electrode, an anode and a secondary emission counteracting member arranged between said second deflection electrode and said anode, a cathode resistor interposed in the cathode circuit of said tube, means to couple said first deflection electrode to the control grid of said tube, means to connect said second deflection electrode to said screen grid, means to connect said third deflection electrode to said anode, a second resistor connected to said screen grid, means to short circuit said resistor for currents of frequency of said signal voltage, means to apply operating potentials between said cathode resistor and said anode and said second resistor, means to apply a signal voltage to the control grid of said tube, and a resonant circuit connected to said anode.

4. An amplifier circuit arrangement, comprising an electron discharge tube having an electron-emitting cathode, a control grid, a screen grid, an electron beam deflection system comprising a first deflection electrode, second and third deflection electrodes arranged in cooperative association with said first deflection electrode, an anode and a secondary emission counteracting member arranged between said second deflection electrode and said anode, a first resonant circuit interposed between the grid and the cathode of said tube, a cathode resistor interposed in the cathode circuit of said tube, means to connect said first deflection electrode to said first resonant circuit, means to connect said second deflection electrode to said screen grid, means to connect

said third deflection electrode to said anode, a second resistor connected to said screen grid, means to short circuit said resistor for currents of frequency of said signal voltage, means to apply operating potentials between said cathode resistor and the anode of said tube and said second resistor, means to apply a signal voltage between said cathode resistor and said first resonant circuit, and a second resonant circuit connected to said anode to produce an output signal voltage.

5. An amplifier circuit arrangement, comprising an electron discharge tube having an electron-emitting cathode, a control grid, a screen grid, an electron beam deflection system comprising a first deflection electrode, a second deflection electrode and a third deflection electrode arranged in cooperative association with said first deflection electrode, an anode and a secondary emission counteracting member arranged between said second deflection electrode and said anode, said third deflection electrode being connected to said anode, means to connect said second deflection electrode to said screen grid, a first resonant circuit having one terminal thereof connected to the grid of said tube, a cathode resistor having one terminal thereof connected to the cathode of said tube, a capacitor coupling the remaining terminals of said resonant first circuit and said cathode resistor, means to connect said first deflection electrode to the remaining terminal of said first resonant circuit, a second resonant circuit having one terminal thereof connected to said anode, a resistor connected between said screen grid and the remaining terminal of said second resonant circuit, means to apply operating potentials to said remaining terminals of said cathode resistor and said second resonant circuit, means to apply a signal voltage between said remaining terminals of said cathode resistor and said first resonant circuit, and a capacitor coupling said screen grid to said cathode, said capacitor having a slow reactance value for voltages of the frequency of said signal voltage.
